PROCESS FOR COOLING A GAS

Willem Pieter Hendal, Amsterdam, Netherlands, assignor to Shell Development Company, New York, N. Y., a corporation of Delaware

Application November 12, 1954, Serial No. 468,487

Claims priority, application Netherlands November 20, 1953

1 Claim. (Cl. 62—5)

This invention relates to a process for cooling a gas by expanding it in a vortex tube, and to an improved vortex tube for the purpose.

The so-called vortex tube, also called a Ranque tube or a Hilsch tube, appears to have been discovered first by Georges J. Ranque, the construction and some of the operating features of such a tube being described in U. S. Patent No. 1,952,281, issued March 27, 1934 to Ranque. A bibliography of publications on the vortex tube has been published by W. Curley and R. MacGee, Jr., in Refrigerating Engineering, vol. 59, 1951, pages 166 and 191-193. As set forth in the aforementioned patent and the prior art referred to in the mentioned bibliography, the vortex tube may include a chamber having the shape of a surface of revolution, such as a cylinder, this chamber having an inlet pipe for tangentially introducing the gas to be treated into a central region of the chamber. A gyratory motion is imparted to the gas as it enters the chamber, and means are provided to divide the gas into two concentric sheets moving along each other. If part of the gas is discharged at a point in or near the center line of the tube and another part at a point on the periphery of the tube, the result is that the former part has become colder and the latter part warmer than the entering gas. This phenomenon which occurs in the vortex tube during expansion of the gas will hereinafter be referred to as the heat separation effect. This heat separation effect results in the vortex tube (in an uncooled tube) becoming hot at least for a portion thereof and this will be referred to as the hot side of the vortex tube.

It has been proposed, according to German Patent 858,260 to increase the heat separation effect of the vortex tube by providing an apparatus in the tube by which the peripheral hot gas is separated from the central cold gas almost immediately in the vicinity of the inlet end; mixing of the hot with the cold gas would thus be avoided, and it would be possible to reduce the length of the vortex tube considerably. It is also proposed in the patent to cool the hot gas thus separated, and to mix the cooled hot gas with the cold gas either in the vortex tube itself or outside it. In order to effect the mixing in the vortex tube itself, a lengthening-piece, into which the hot gases only are able to pass, is provided to the actual vortex tube, which is very short; after being separated from the cold gases the hot gases are then cooled in the lengthening-piece by free convection, for which purpose it is provided with cooling ribs. After the gases have passed through the lengthening-piece they are led into the central part of the vortex tube itself and there mixed with the cold gas.

Now, in accordance with the present invention, it has been found that the heat separation effect of the vortex tube can be improved considerably. The means for accomplishing this improvement will be described with reference to the accompanying drawing, wherein:

Fig. I is a diagrammatic representation of a vortex tube provided for external cooling;

2

Fig. Ia is a view partly in cross-section of Fig. I taken at Ia—Ia;

Fig. II is a diagrammatic representation of a vortex tube provided for internal cooling; and

Fig. IIa is a view partly in cross-section of Fig. II taken at IIa—IIa.

It has now been discovered that the heat separation effect is enhanced considerably by expanding a gas in a vortex tube which is empty at the place where the heat separation effect occurs and intensively cooling the tube. Accordingly, there are no structural means in the hot end of the tube for separating peripheral hot and central cold gases. Also, the cooling is so intensive that when approximately 15% to 20% of the gas introduced is transported from the vortex tube as hot gas, the absolute temperature of the hot gas is not more than approximately 15% and preferably not more than 3% higher than the absolute temperature of the gas introduced.

In this connection it is to be noted that although the cooling ribs of the apparatus described in the above-mentioned German patent extend over part of the actual vortex tube, it is not intended to cool the vortex tube itself, but only the lengthening-piece, which amounts to an attachment only and effects no vortex tube heat separation effect itself. There is actually no appreciable cooling of the vortex tube per se.

The improvement in the heat separation effect by the practice of the present invention may be considered to be unexpected; those skilled in the art might have expected that intensive cooling of the hot gas flowing along the vortex tube would cause a disturbance in the process and/or in the vortex pattern occurring in the tube, and would be confirmed in this expectation by the contents of the German patent which prescribes cooling of the hot gas outside the actual vortex tube. The cooling which is effected according to the German patent is caused by free convection of air. Presumably this method of cooling was considered heretofore to be as effective as any other since it would serve no useful purpose to increase considerably the transport of heat from the wall of the tube to the outside as compared to the transfer of heat from the hot gases to the wall.

It has been discovered, however, that there is a very large transfer of heat from the gases to the wall of the tube, provided the flow in the tube is not disturbed; and then a useful purpose is served by improving the transport of heat from the wall of the tube to the outside. In the vortex tube proposed in the German patent, however, the flow is disturbed in the immediate vicinity of the inlet end of the gases by the presence of means for separating the hot gas from the cold gas and consequently no great transport of heat is possible in that case.

In connection with the fact that the above-mentioned separating means in the vortex tube of the German patent extends to a point at which the gases still have a considerable amount of kinetic energy (e. g. the point at which the heat separation effect occurs), the yield of cold, as measured either by the minimum temperature of the exiting cold gas stream or by the product of the fraction which exits as cold gas times the difference in temperature between it and the entering gas, from the vortex tube according to the German patent is less than the yield from the tube in accordance with the present invention.

For carrying out the present process it is advantageous to use a vortex tube, as represented in Fig. I, which is provided with a cooling jacket 12 at least over the length of the empty part. Preferably an empty tube 11 is used (with inlet and discharge ends for the gases fitted in a manner already known) which is provided with a cooling jacket over the whole of its length. The inlet 13 of the cold coolant, for example cooling water, is gen-

erally provided on the hot side of the vortex tube, i. e. on the side of the gas inlet 14 away from the side on which the diaphragm 15 is placed through which the axial cold gas stream is withdrawn, but it is also possible to provide the coolant inlet elsewhere, for example near the gas inlet or the discharge end for the cold gases. The valve 16 provided in the hot end of the tube is adapted to control the proportion of gas which is withdrawn from the tube at the hot end, permitting the exit of a portion of the total gas as hot gas, or none at all.

Referring to Fig. II, there is shown a vortex tube 21 which is adapted to be cooled directly on the inside by means of a cold liquid flowing along the inner wall of the vortex tube, delivered thereto by coolant inlet 22, which is suitably placed near the gas inlet 23. As a result of the centrifugal force and the helical movement of the gas the cooling liquid moves along the inner wall of the vortex tube in the form of a film. The cooling liquid is discharged from the hot gas discharge end of the vortex tube together with hot gas discharged therefrom. The cooling liquid is suitably discharged from one or more points, if desired, and when none of the gas is discharged from the hot end, the cooling liquid is discharged alone, except for that portion which is vaporized and atomized with the gas stream and carried out with the cold gas stream.

It will be understood that both methods of cooling can be utilized at the same time, with the same vortex tube being adapted for both external and internal cooling.

The inlet end of the vortex tube, according to the invention, is preferably provided close to the discharge end for the cold gas, i. e. near the diaphragm which defines the axial stream outlet.

The length of the empty part of the tube (the distance from the gas inlet to the central discharge for the cold gases is here left out of account) is usually large with regard to the diameter of the tube, as follows:

If no gas is discharged on the hot side of the vortex tube the length of the empty part is at least 6 times the diameter of the tube. Very good results are obtained with a length 9 to 10 times the diameter, but the maximum effect is found to be produced with a still greater length, approximately 18 to 20 times the diameter.

If a portion of the gas is discharged on the hot side of the vortex tube the length of the empty part thereof may be somewhat smaller, e. g. at least 3 to 4 times the diameter, the preferred length being at least 9 times the diameter of the tube. In this case, as in the case where no gas is discharged on the hot side, the maximum effect to be obtained is produced when the tube is longer. In both cases, therefore, the length may be 18 or more times the diameter of the tube.

The maximum quantity of cold is produced when between 10% and 30%, preferably approximately 20% of the gas introduced is discharged on the hot side of the vortex tube. By quantity of cold is meant the product of the proportion (μ) of the gas which is discharged as cold gas times the difference (ΔT) between its temperature and the temperature of the entering gas. In the present process it is also possible to remove no gas at all on the hot side, e. g. when in a closed system it is desired not to lose any gas, so that the whole amount of gas is produced as cold gas (the vortex tube then need have only the one central or axial discharge opening).

In the process according to the invention, it is possible to regulate and/or adjust the temperature of the effluent cold gas in a simple way by regulating the velocity of the coolant (often cooling water) flowing through the cooling jacket or along the inner wall of the vortex tube.

The gas to be introduced may originally be compressed and expansion may occur against the pressure of the atmosphere. Since the heat separation effect depends on the ratio of initial to final pressure—which ratio often has an approximate value of about 5—expansion of the gas under normal or increased pressure against a vacuum

gives a still better heat separation effect. Expansion into a vacuum is suitable when, for example, two or more vortex tubes are connected in series, in which case the gas expands in stages.

Having described the invention and the various features of it which come into consideration in its practice, the application of the invention and the advantages to be derived from its practice will be set forth in the following illustrative examples.

10

Example I

30 kilograms of air per hour (temperature approximately 22° C.) were led at a pressure of 4.5 atmospheres into an empty vortex tube having an inside diameter of 15 mm., a length of 190 mm., a tangential rectangular inlet of 6.72 sq. mm., and a central discharge opening for cold gas of 6 mm. diameter. The vortex tube, which was provided with a cooling jacket, was intensively cooled with water of a temperature of approximately 10° C. The entire amount of the air was obtained as cold gas having a temperature of -14° C. (no hot gas discharge).

In contrast to the above, a similar operation with the exception that no cooling of the vortex tube except by the adjacent air, resulted in a maximum wall temperature of 200° C., and the temperature of the gas drawn off at the central discharge opening is essentially equal to the inlet temperature of the gas, i. e. about 22° C.

30

Example II

A mixture of carbon monoxide and water vapor was converted to form carbon dioxide and hydrogen in a plant at 550° C. in two converters, each containing 70 tons of a catalyst of iron and chromium oxides.

These converters have to be put out of operation from time to time to permit inspection, and for this purpose it is necessary to cool them to approximately 25° C. Cooling is first effected by steam and then with cold nitrogen. Formerly nitrogen of approximately 3° C. was used for this purpose, but now nitrogen of this temperature under a pressure of 6 atm. is led into an empty vortex tube, cooled by water of 16° C., in a quantity of 1200 cubic meters per hour.

The dimensions of this vortex tube are:

Inner diameter	cm	7.6
Length	cm	190
Area of gas inlet	sq. cm	3
Diameter of discharge for cold gases	cm	4.8

15 Fifteen (15) percent of the gas introduced was removed from the hot side of the vortex tube by means of a valve; in this way a maximum quantity of cold was produced. The cooling of the tubes was of sufficient intensitvity to give a cooled nitrogen stream of -30° C., while the hot gas had a temperature of approximately 40° C.

In order to prevent the occurrence of undesirable stresses in the material of the converters at the beginning of the cooling period caused by too great differences of temperature between the hot converters and the cold gas, use was made of the possibility of allowing the temperature of the cold gas to decrease gradually by regulating (gradually increasing) the velocity of the cooling water.

60 By using this new and simple method of cooling, the cooling period of the converters was reduced by a day and a half, which means a very considerable improvement in the operating yield of the converter installation.

Example III

The effect of the intensitvity of cooling on the operation of a vortex tube according to the invention is seen from the following tests. Compressed air (6 atm. abs.) was allowed to expand into an empty vortex tube, provided with a cooling jacket, the dimensions being as follows:

Inner diameter of the tube	mm	10

Length of the tube.....	mm.....	195
Area of gas inlet.....	sq. mm.....	5.12
Diameter of central discharge for cold gases.....	mm.....	6
Diameter of cooling jacket.....	mm.....	16
Length of cooling jacket.....	mm.....	200

The cooling water and the air introduced were at the same temperature (13.5° C). The difference in temperature between the cold gases and the gas introduced is indicated by Δt ; the temperature of the hot gases by t_w .

(a) Approximately 15% of the gas introduced was drawn off on the hot side. When the quantity of cooling water was increased from 5 liters per hour to 200 liters per hour, Δt increased from 29.5 to 34 degrees centigrade, while t_w decreased from 45° C to 22.5° C .

(b) No gas at all was drawn off on the hot side. When the quantity of cooling water was increased from 5 liters per hour to 500 liters per hour, Δt increased from 23.9 to 28.4 degrees centigrade.

From the above data it follows that with the present vortex tube the coefficient of heat transmission was of the order of 1000 kcal. per hour per square meter per degree centigrade. On the other hand, with the free convection cooling described in the German patent already referred to, this coefficient is only of the order of 10 kcal. per hour per square meter per degree centigrade, being only about one percent (1%) of the value in accordance with the present invention. Thus, the present cooling is therefore intensive as compared to the cooling by free convection. Even a ten-fold increase would represent a substantial advantage in the use of the present invention.

Example IV

In order to demonstrate the material and undesirable effect of the presence of structural bodies in the vortex tube over the part where the heat separation effect occurs, a concentric, open hollow tube with a smaller diameter than the inner diameter of the vortex tube was placed in the vortex tube mentioned in Example III. This hollow tube formed a slot-shaped space of over 1 mm. 40 with the inner wall of the vortex tube. Openings were provided in the hollow tube at the discharge end for the hot gases so that there was a local connection between the slot-shaped space and the central part of the tube. 45

During the tests the pressure of the compressed air was

6 atm. abs. The temperature of the air was the same as that of the cooling water, namely, 14° C . The velocity of the cooling water was about 300 liters per hour.

(a) Approximately 15% of the hot gas was drawn off. 5 When the end of the hollow tube extended so far into the vortex tube that the empty part of the vortex tube had a length (l) equal to the diameter (d) of the vortex tube, $t=6.5$ degrees centigrade. When $l=3d$, $t=26$ degrees centigrade; when $l=10d$, $t=33.5$ degrees centigrade.

10 (b) No hot gas was drawn off. When $l=d$, $t=12$ degrees centigrade; when $l=6d$, $t=25.5$ degrees centigrade; when $l=10d$, $t=28$ degrees centigrade.

I claim as my invention:

In a process for producing cold in a gas stream utilizing 15 a vortex tube wherein the gas stream is divided into a peripheral outer hot portion and a central cold portion and wherein there is a heat separation zone for transferring heat from the central cold portion to the outer hot portion, said vortex tube being unobstructed along 20 its length where the heat separation effect occurs, the improvement comprising intensively cooling the gases of the heat separation zone by direct heat exchange with a liquid coolant flowing along at least a portion of the inner wall of the vortex tube enclosing said heat separation zone, and thereby facilitating the transfer of heat from the central cold portion to the outer hot portion, resulting in a lower temperature in said cold portion than obtainable in the absence of said flowing liquid coolant.
